(57) **CLAIM**

The ornamental design for a detailing brush, as shown and described.

DESCRIPTION

FIG. 1 is a perspective view of a detailing brush, shown in an environment of use;

FIG. 2 is a left side elevational view of the detailing brush;

FIG. 3 is a right side elevational view of the detailing brush;

FIG. 4 is a rear side elevational view of the detailing brush;

FIG. 5 is a front side elevational view of the detailing brush;

FIG. 6 is a bottom plan view of the detailing brush; and,

FIG. 7 is a top plan view of the detailing brush.

The dot-dash broken lines illustrate environmental structure and form no part of the claimed design. The dash-dash broken lines illustrate portions of the article and form no part of the claimed design.

1 Claim, 7 Drawing Sheets
